LOCK.

1,195,514.

Specification of Letters Patent. Patented Aug. 22, 1916.

Application filed January 20, 1912. Serial No. 672,440.

To all whom it may concern:

Be it known that I, JOHN H. SHAW, of the city and county of New Haven and State of Connecticut, have invented certain new and useful Improvements in Locks, of which the following is a full, clear, and exact description.

This invention relates to locks, and it has special reference to locks of the type where-
10 in a latch bolt is retractable from the outside of the door by a cylinder lock, and is also retractable by inside and outside knobs, there being suitable night latch mechanism associated with the outside knob to dog or
15 release the same. Certain features of the invention, however, are applicable to locks of other types.

The invention has among its objects the provision of key mechanism operable by a bolt retracting master key to block the retraction of the latch bolt from the outside of the door by the knob mechanism and by the change key; the provision of means at one side (the inside) of the door to dog the
20 outer manual retracting device for the latch bolt and simultaneously block the operation of the key actuated means at the other side (the outside) of the door; the provision of means whereby a cylinder lock at one side of
25 the door is operable to block the operation of a cylinder lock at the opposite side of the door; the provision of a lock in which a master key inserted at one side of the door blocks the operation of a change or ordinary key at the opposite side of the door; and the general improvement in construction and operation of devices of the class to which my invention relates.

The foregoing and other novel features
40 of the improved lock will appear clearly from the following description and claims.

In the accompanying drawings which illustrate a preferred form of the invention, Figure 1 is an elevation of the lock, with the cap plate removed, showing the parts in their normal position, with the night latch mechanism "off," the latch bolt being retractable by the regular key inserted at the outside of the lock; Fig. 2 is a similar view,
45 showing the position of the parts when the door is closed, the night latch mechanism being dogged or deadlocked by the actuation of the master key from the inside; Fig. 3 is a view similar to Fig. 2, but showing the retraction of the latch bolt by means of the master key inserted at the outside of the

lock; Fig. 4 is a fragmentary view of the lock in the position shown in Fig. 3, illustrating the blocking of the regular key when the parts are in the position indicated; Figs. 60 4^A and 4^B are transverse sections of the lock through the cylinders showing the change key or regular key and the master key, respectively, inserted into the outside cylinder lock. Fig. 5 is a rear face view of the outer 65 duplex cylinder lock; Fig. 6 is a section on line 6—6 of Fig. 2; Fig. 7 is a detail face view of the key actuated slide which dogs the night latch mechanism and blocks the actuation of the regular key; Fig. 8 is an 70 edge view of said slide; Fig. 9 is a detail view showing the dogging of the upper thumb slide of the night latch mechanism by the key actuated means; Fig. 10 is a detail face view of the latch bolt retracting 75 lever, and Fig. 11 is a top view of the levers shown in Fig. 6, illustrating more clearly their coöperation with the key actuated slide.

Referring to the drawings, the lock case 30 15, having the face plate 16, is shown as containing a spring protracted latch bolt 17 which is retracted by means of a yoke 18 actuated in the well-known manner by inner and outer roll-backs 19, 20, respectively. 65 The outer roll-back 20 is dogged in the usual manner by means of a thumb slide 21 projecting through the face of the lock, said thumb slide being retractable from its dogging position by means of a second thumb 20 slide 22 also projecting through the face of the lock and connected with the slide 21 by the well known connecting lever or walking beam 23, fulcrumed in the case at 24. In order to hold the slide 21 firmly in either 95 its dogging or non-dogging adjustment the customary retaining spring 25 and retaining lug 26 are employed.

The means for retracting the latch bolt 17 by a key inserted at the outside of the 100 lock comprises an irregularly shaped bell crank or elbow lever 27 (Fig. 10), pivoted in the upper part of the case at 28, and having a depending branch or arm 29 to coöperate with a cross-head 30 on the rear 105 end of the latch bolt stem. The other arm or branch 31 of the elbow lever 27 has at its free extremity a relatively wide head or enlargement 32 which extends transversely 110 across the case, closely adjacent the periphery of the inner cylinder lock 34, and also closely adjacent the periphery of an outside

cylinder lock 35 (Fig. 5) inserted in the outer wall of the case in line with the cylinder lock 34.

Pivoted in the upper part of the case at 5 36 are parallel levers 37, 38, having enlarged beveled heads 37^a, 38^a, respectively, at their free ends, which heads rest side by side on the upper surface of the extremity 32 of the latch retracting lever, as shown in 10 Fig. 6. The lever 38 is provided near its free end with a lateral extension or lug 38^b coöperating with an upwardly directed arm 39 of a key actuated slide 40, having an upwardly directed extension or bit 41 adapted 15 to be contacted by the short bit 33 of the inside lock cylinder 34, as shown in Figs. 1 and 2. The slide 40 is located over a portion of the latch bolt retracting lever, as shown, and it is guided for lateral movement 20 in the case by means of a forked portion 42 fitting over a suitable guide or lug 43 on the back of the case. Said slide is also guided by means of the extension or bit 41 thereon, a portion of which is directed horizontally over and rests freely on 25 a portion of the arm 31 of the bolt retracting lever. The slide is further guided by means of oppositely placed guides 44, 45, between which is located a lateral extension 30 46 on the slide, the purpose of which will hereinafter appear. The arrangement is such that when the slide 40 is in the position shown in Fig. 1, its upwardly directed arm 39 will be clear of the projection 38^b on 35 the outer lever 38, thereby permitting said lever to be depressed in order to actuate the lever 27 to retract the bolt. However, when the slide 40 is in the position shown in Fig. 40 2, the arm 39 will have its extremity immediately beneath the projection 38^b preventing 45 a depression of the lever 38. The slide 40 is moved into either of the positions indicated in order to dog or release the lever 38, by means of a master key inserted in the cylinder lock 34 and capable of rotating the short bit 33 in either direction, to move the dogging slide correspondingly. (Figs. 1 and 2.)

The dogging or blocking of the lever 38 50 by means of the slide 40 set by the master key from the inside of the door, prevents the operation of the regular key or change key at the outside of the door. The regular key actuates the bit 47 of the outer cylinder lock 35, and in view of the fact that the bit or dog 47 is in line and rotatable into contact with the head 38^a of the lever 38 (blocked by the arm 39) the bit or dog 47 55 will be arrested in the position indicated in dotted lines in Fig. 4, it being impossible for it to depress the arm 31 of the latch bolt retracting lever. The master key, however, is always operative from the outside of the door, in view of the fact that said key when 60 inserted in the cylinder lock 35 will only ro-

tate the bit or dog 48, which is out of alignment with the blocked lever 38, and is therefore free to depress the lever 37, which, by its engagement with the wide head 32 of the latch bolt retracting lever, causes the latter 70 to be actuated to withdraw the bolt. Preferably, the outer cylinder lock 35 is of the general type disclosed in my Patent No. 830,013, dated September 4, 1906, having a tumbler controlled sleeve 35^a surrounding 75 the key plug 35^b. The change key rotates both the key plug and sleeve, and therefore rotates the bits or rollbacks 48, 47 which are connected to the key plug and sleeve respectively. The master key, on the other 80 hand, rotates the key plug individually, and therefore turns the bit or rollback 48 without moving the bit or rollback 47. When the slide 40 is moved out of coöperation with the lever 38, by the rotation of 85 the bit 33 of the inside lock cylinder in the direction of the arrow, Fig. 1, the bit 47, actuated by the regular key from the outside of the door will not be blocked, inasmuch as said bit may then move the lever 38 downward to actuate the bolt retracting lever. 90

The dog or bit 33 is, as previously stated, freely rotatable in opposite directions in order to shift the slide 40 into and out of its dogging position, and inasmuch as said dog or bit is relatively short it will not, in rotating, contact with any part of the lock, except the bit or extension 41 of the dogging slide. The bits 47 and 48 of the outer cylinder lock, on the other hand, have stop means 95 associated therewith to prevent them from contacting with the dogging slide. When said bits are moved in the direction of the arrow, shown in Fig. 4, they will of course operate the lever 27 before reaching the bit or extension 41 of the slide. If said bits are rotated in the opposite direction, they will be arrested before contacting with the slide 40, by stop means such as a suitable pin 49 carried by the cap plate of the case. 100

The slide 40 has, in addition to the function above described, the function of dogging the night latch mechanism in its "on" position. This is effected in part by means 115 of the hereinbefore described arm 46 on said slide which is adapted to actuate a pivoted dogging member or cam 50, pivoted at 51 to the wall of the case. The cam 50 has a cam surface 52 (Fig. 9) adapted to coöperate with the rear extremity 53 of the night latch slide 22. The arm 46 of the slide 40 actuates the cam 50, by means of a slotted connection embodying a pin or projection 54 on the end of the arm 46, taking into a slot 55 in the cam. Supposing the night latch mechanism to be "on", in which case the upper slide 22 will be protracted, the movement of the slide 40 into the position shown in Fig. 2, by an actuation of the master key 120 at the inside of the door, will produce a 125

downward swinging of the cam 50 on its pivot 51 into the position shown in Fig. 9, in which the cam is held frictionally against the rear extremity 53 of the slide 22, thereby effectively deadlocking said slide. Supposing, on the other hand, that the night latch mechanism is inoperative, the releasing member 22 being retracted, then the actuation of the slide 40 in the manner just described will move the cam against the rear end of member 22 and thereby shift the night latch mechanism into, and lock it in, the operating position. It will therefore be understood that the invention comprises means operable by a master key at the inside of the door for dogging the night latch mechanism, and simultaneously rendering inoperative the regular key, it being understood of course that the regular key will not at any time actuate the bit of the inner lock cylinder. Hence it will be seen that when the master key has been operated to throw the dogging slide 40 into its operative position the ordinary or regular key will no longer operate the lock in any manner, and the outer roll-back will be dogged until the master key returns the slide 40 to its inoperative position.

When the door is closed, the latch bolt 17 is automatically deadlocked by means such as the deadlocking lever 56, pivoted on the pivot 51, and urged into the path of the bolt by a spring 57. Said spring, however, is rendered inoperative when the door is open by a spring protracted guard bolt or controlling member 58 having a hook 59, which when said guard bolt is protracted holds the deadlocking lever 56 out of the path of the latch bolt. When the door is closed, the guard bolt 58 is forced and held inwardly by the strike plate, in the well-known manner, as shown in Fig. 2, whereby the hook 59 is moved into a position wherein it permits the spring 57 to throw the head of the deadlocking lever into a position back of the latch bolt head and also back of the head of the night latch slide 22. Both of said last named members will then be effectively deadlocked. On retracting the latch bolt by either roll-back or by the key actuated means, a shoulder 60 on the lever 27 will contact with a shoulder 61 on the tail of the deadlocking lever and thereby throw said lever out of the path of the latch bolt, the construction being such that the deadlocking lever is moved out of the way of the latch bolt before the retraction of the latter is begun. The means for deadlocking the latch bolt and one of the slides of the night latch mechanism by means of a guard bolt or controller coacting with the strike plate does not, however, form any part of the present invention.

While the foregoing description is a detailed one in so far as it concerns the particular embodiment of my invention selected

for illustration, it will of course be understood that the invention is susceptible of numerous other embodiments within the scope of the appended claims.

What I claim is:—

1. In a lock the combination with a latch bolt, key operated means for retracting the same, a manually operable retracting means for the bolt, night latch mechanism associated with said last named means, and other key operated means which renders the first named key operated means and said night latch mechanism inoperative; substantially as described. 70

2. In a lock the combination with a latch bolt and manually operable retracting means therefor at one side of the door, of night latch mechanism to dog said retracting means comprising slides projecting through the face of the lock, a slide operated by a key at the inside of the door, and means operated by said last named slide to move one of said night latch slides; substantially as described. 80

3. In a lock, a latch bolt, manual retracting means therefor at the outside of the door, a change key, mechanism operable by said change key to retract said bolt from the outside of the door, a master key adapted to retract said bolt from the outside of the door, and means actuated by said master key from the inside of the door to block the retraction of said bolt by both said manual retracting means and by said change key; substantially as described. 90

4. In a lock, a mortise case, a cylinder lock secured thereto, a plurality of rollbacks on said cylinder lock within said case, mechanism in said case adapted to be actuated by said rollbacks, one of said rollbacks being 105 rotatable independently of the other, and means for preventing the operation of one of said rollbacks; substantially as described.

5. In a lock, a mortise case, a cylinder lock secured therein, a plurality of rollbacks on said cylinder lock, a key to rotate all of said rollbacks simultaneously, another key to rotate one of the rollbacks individually, mechanism in the case adapted to be actuated by said rollbacks, and a blocking device adapted to be moved into the path of one of said rollbacks to prevent the rotation thereof; substantially as described. 110

6. In a lock, a cylinder lock, a plurality of rollbacks carried thereby, one of said rollbacks rotatable independently of the other, a change key adapted to said cylinder lock for rotating at least one of said rollbacks, a master key adapted to said lock for operating another rollback, and means actuated by said master key to prevent the operation of said change key; substantially as described. 120

7. In a lock, a cylinder lock, a plurality of rollbacks carried thereby, a key to operate 130

said rollbacks simultaneously, another key to operate one of said rollbacks individually, and means operated by one of said keys to prevent the actuation of said cylinder lock by the other key; substantially as described.

8. In a lock the combination of a latch bolt, retracting means for said latch including a single cylinder lock bolt actuated by different keys inserted from the outside of the door, and means actuated by one of said keys from the inside of the door to block the operation of said first named means by the other key; substantially as described.

9. In a lock the combination of a latch bolt, retracting means therefor including a single cylinder lock operated by different keys from the outside of the door, a cylinder lock for one of said keys at the inside of the door, and means operated by said cylinder lock to block said retracting means against operation by the other key; substantially as described.

10. In a lock the combination of a latch bolt, means for retracting the same from the outside of the door comprising a cylinder lock operable by a master key and an ordinary key, and means comprising a cylinder lock at the inside of the door operable by the master key, to block said retracting means against operation from the outside by means of the ordinary key; substantially as described.

11. In a lock the combination of a latch bolt, retracting means therefor operable from the outside of the door and comprising a cylinder lock with a plurality of bits, and means, comprising a cylinder lock at the inside of the door, to block one of said bits; substantially as described.

12. In a lock the combination of a latch bolt, means for retracting the same comprising a cylinder lock at the outside of the door having different bits, one of said bits being operable by one key and another by another key, and means comprising a cylinder lock at the inside of the door and operable by one of said keys alone, to block said retracting means against operation by the other key; substantially as described.

13. In a lock the combination of a latch bolt, retracting means therefor comprising a cylinder lock at the outside of the door having two bits, one of said bits being operable by a master key, and the other being operable by an ordinary key, and means comprising a cylinder lock at the inside of the door operable only by the master key, to block the movement of the bit actuated by an ordinary key; substantially as described.

14. In a lock the combination of a latch bolt, retracting means therefor comprising a cylinder lock at the outside of the door having two bits, one of said bits being operable by a master key alone, and the other

being operable by an ordinary key, and means comprising a cylinder lock at the inside of the door operable only by the master key, to block the movement of the bit actuated by an ordinary key, said blocking means also comprising a slide movable laterally in the case by direct engagement with the bit of the inner cylinder lock; substantially as described.

15. In a lock the combination of a latch bolt, manually operable retracting means therefor at opposite sides of the door, night latch mechanism to dog one of said retracting means, means actuated by a master key and an ordinary key at the outside of the door for retracting said bolt independently of said manually operable means, and means operable by a master key from the inside of the door to block said key actuated means against operation by an ordinary key from the outside and to lock said night latch mechanism in its operative position; substantially as described.

16. In a lock the combination with a latch bolt, manually operable retracting means therefor, night latch mechanism associated with said retracting means, key operated means at the outside of the lock to retract said bolt, and a key operated member operable to block said key operated means and to render said night latch mechanism inoperative; substantially as described.

17. In a lock the combination of a latch bolt, manually operable retracting means, night latch mechanism associated with said retracting means, key operated means at the outside of the lock to retract said bolt, and a key actuated slide in the case operable to block said key operated means and to render said night latch mechanism inoperative; substantially as described.

18. A lock comprising a bolt, manually operable retracting means therefor, night latch mechanism associated with said means, key operated retracting means at one side of the door, a slide operated by a key at the other side of the door, means coacting with said slide to block the operation of said key actuated retracting means, and other means coacting with said slide to lock said night latch mechanism in a predetermined position; substantially as described.

19. In a lock, a bolt, retracting means therefor comprising a cylinder lock at the outside of the door having a plurality of bits, and means operable from the inside of the door to block one of said bits; substantially as described.

20. In a lock, a bolt, retracting means therefor comprising a cylinder lock at the outside of the door having a plurality of bits, and means operable by a cylinder lock at the inside of the door to block one of said bits; substantially as described.

21. A lock comprising a bolt, a plurality

of levers actuating said bolt, a cylinder lock at the outside of the door having a plurality of bits coöperating with said levers, and means actuated by a cylinder lock at the 5 inside of the door, to block the operation of one of said levers; substantially as described.

22. A lock comprising a bolt, a retracting lever therefor, pivoted members supported on the end of said retracting lever, inner 10 and outer cylinder locks having bits or dogs to coact with said members, and a slide operative by one of said cylinder locks to block one of said members; substantially as described.

23. In a lock, a bolt, retracting means therefor, night latch mechanism associated with said retracting means and comprising a dogging slide and a releasing slide, a cam having a cam surface to engage the rear end 20 of said releasing slide, and means for operating said cam from the outside of the lock; substantially as described.

24. In a lock, a case, a cylinder lock in one wall of the case having a plurality of dogs, 25 devices in the case adapted to be operated by said dogs, and means including a cylinder lock in the opposite wall of the case to block one of said dogs without blocking another dog; substantially as described.

25. In a lock, a latch bolt, separate retracting means therefor at the outside of the door, and key mechanism operable from the inside of the door to block the operation of both of said means; substantially as de- 35 scribed.

26. In a lock, a latch bolt, manual retracting means therefor, night latch mechanism associated with said means, key actuated retracting means for said latch bolt, and means 40 operable from the side of the door opposite said key actuated means to render the latter inoperative and to shift said night latch mechanism into operative position; substantially as described.

27. In a lock, a latch bolt, means including a cylinder lock at one side of the door, to retract said latch bolt, a manual retracting means for said latch bolt at the same side of the door as said cylinder lock, and a 50 cylinder lock mechanism at the opposite side of the door to block the operation of said first cylinder lock and having operative connection with said manual retracting means to dog the latter; substantially as described.

28. In a lock, a latch bolt, mechanism to retract said latch bolt operated by a plurality of different keys, manual retracting means for said latch bolt at the same side of the door, and dogging means for both of 55 said retracting means operative from the op-

posite side of the door by one of said keys but inoperative by another of said keys; substantially as described.

29. In a lock, a latch bolt, manual retracting means therefor, key mechanism for re- 65 tracting said latch bolt, operated by a master key and an ordinary key from one side of the door, and means at the opposite side of the door, operated by a master key only, to dog said manual retracting means; sub- 70 stantially as described.

30. In a lock, a latch bolt, manual retracting devices therefor at opposite sides of the door, mechanism operated by a plurality of 75 keys to retract said latch bolt from the outside of the door, a dogging means for the outer manual retracting device, and means at the inside of the door actuated by one of said keys to operate said dogging means; substantially as described. 80

31. In a lock, a bolt, a cylinder lock for operating the same from one side of the door, actuated by a plurality of different keys, and a cylinder lock mechanism at the opposite side of the door operative to prevent 85 the actuation of said bolt by one of said keys; substantially as described.

32. In a lock, a latch bolt, a cylinder lock at one side of the door operative by a plurality of different keys to retract said latch 90 bolt, and a cylinder lock mechanism at the opposite side of the door operative by one of said keys to prevent the retraction of said latch bolt from the first side of the door by another key or keys; substantially as de- 95 scribed.

33. In a lock, a latch bolt, manual retracting means therefor at one side of the door, key actuated retracting means for said latch bolt at the same side of the door and includ- 100 ing a cylinder lock operated by a plurality of keys, and a cylinder lock mechanism at the opposite side of the door operative by one of said keys to dog said manual retracting means; substantially as described. 105

34. In a lock, a latch bolt, manual retracting means therefor, night latch mechanism associated with said means, mechanism for retracting said latch bolt by means of a master key and an ordinary key, and means in the lock case, operative by said master key only, to dog said night latch mechanism in its operative position; substantially as de- 110 scribed.

In witness whereof I have hereunto set 115 my hand on the 17 day of January, 1912.

JOHN H. SHAW.
